CONTROL FOR REFRIGERATING MACHINES.

1,424,826.

Specification of Letters Patent. Patented Aug. 8, 1922.

Application filed March 2, 1920. Serial No. 362,756.

To all whom it may concern:

Be it known that we, ALFRED D. KARR and KARL D. PERKINS, both citizens of the United States, and residing, respectively, at Newark, county of Essex, State of New Jersey, and New York, county of New York, and State of New York, have invented certain new and useful Improvements in Controls for Refrigerating Machines; and we do hereby declare the following to be a full, clear, and exact description of the invention, such as will enable others skilled in the art to which it appertains to make and use the same.

15 The present invention relates to a system of thermostatic control for refrigerating machines, particularly of the Audiffren type in which the apparatus comprises a pair of rotary communicating vessels, sometimes called a "dumb-bell" from their resemblance thereto. In one of the vessels or bells which is usually known as the compressor bell, the refrigerating fluid is compressed, and in the other bell which is known as the expansion bell the fluid is expanded to absorb heat from the surrounding medium, which may be the liquid that is to be cooled, or some other liquid, such as brine, that in turn is to be used for cooling the desired liquid.

20 The vessel or bell in which the compression of the refrigerating fluid takes place is partly immersed in the cooling liquid to absorb the heat evolved during compression, there being a continual flow of such liquid

25 through the containing tank which is usually called the "condenser tank" of the apparatus. The cooling liquid is discharged from the condenser tank through an overflow pipe having its inlet end located in

30 the condenser tank at a height sufficient to maintain a level in this tank which will keep the compression bell partially submerged.

35 The supply of cooling liquid to the condenser tank is regulated by means of a small tank, usually called a feed tank, a float, and a valve controlled by the position of the float. The feed tank is located adjacent the condenser tank and is provided with an opening leading to a stand pipe which extends into the condenser tank and terminates near the compressor bell

but above the normal level of the liquid in the condenser tank. The portion of the stand pipe within the condenser tank is provided with an auxiliary or bleeder opening 55 of small diameter, located at or below the normal level of the cooling liquid in the tank. When the compressor bell is rotated a wave of liquid will tend to follow it, and some of this liquid will spill into the stand pipe and 60 flow into the feed tank. The rising liquid in the feed tank will raise the float, thereby opening the valve which controls the supply of cooling liquid. If the bells stop rotating the supply of liquid to the stand pipe will 65 cease, and the feed tank will be slowly emptied through the stand pipe and bleeder into the condenser tank. The ball of the float valve will then drop to cut off the supply of cooling liquid.

70 It has heretofore been proposed to use a thermostat in the cooling or brine tank to control the rotary vessels or bells according to the thermal condition of the liquid in this tank, but such a thermostat is not sufficient to provide for all contingencies of 75 operation, and particularly those due to excessive temperature in the condenser tank, which temperature may result in injury to the vessel located therein unless rotation of 80 the latter is stopped to stop compression of the refrigerating fluid in this vessel.

85 The above defect in apparatus of the character above described cannot be remedied with certainty by the provision of a thermostat in the condenser tank, since the thermostat may be immersed in the liquid therein, and yet the liquid may not be heated because its level may have fallen out of contact with the compressor bell. If this condition exists the thermostat will not be affected, with the result that the controlling mechanism to which it may be connected, will not stop the rotation of the bells. It is accordingly an object of the present invention to improve the arrangement of the feed tank with relation to the condenser tank so as to permit a thermostat to be used effectively in the condenser tank as well as in the refrigerating tank for controlling the 90 rotary parts of the apparatus. It is a further object of the invention to arrange the

thermostatic system so that these instruments will so control the motor which drives the rotary parts of the apparatus as to provide for the various contingencies of operation occurring in practice.

In accordance with the present invention, the stand pipe leading to the feed tank is provided with a small orifice which communicates with the condenser tank at substantially the normal level of liquid therein as determined by the overflow pipe. With this arrangement, if the supply of cooling liquid fails while the bells continue to rotate, liquid supplied to the feed tank through the stand pipe will drain back into the condenser tank, thus maintaining substantially normal liquid level therein. Since the compression bell remains partly submerged, its heat will be imparted to the cooling liquid and if the supply of such liquid is not continuous, the liquid will ultimately become so warm that the thermostat in the condenser tank will be affected and will act through suitable controlling devices to stop the rotation of the bells. The thermostats exercise in general, a joint control, but the one in the cooling or refrigerating tank is to an extent under the domination of the one in the condenser tank, so that the former cannot initiate any movement of the rotary bells unless the latter thermostat is in its normal position, due to a sufficiently low temperature in the condenser tank.

The arrangement of the feed tank, and the manner in which the control of the apparatus is secured by the thermostats, as well as other objects and advantages of the invention, will appear more clearly from a description of certain preferred embodiments thereof as illustrated in the accompanying drawings in which Fig. 1 is a view of the refrigerating machine in side elevation with the thermostatic control system shown diagrammatically;

Fig. 2 is a sectional end elevation through the condenser and feed tanks; and

Fig. 3 shows a modified arrangement of the thermostats.

In the drawings 10 represents the condenser tank and 11 the cooling or refrigerating tank. The rotary parts of the apparatus or "dumb-bell" comprise a spherical compression bell 12 and a cylindrical expansion bell 13. These bells are in communication through a pipe 14 which also serves as a shaft for supporting the bells in suitable bearings at the top of the tanks. The bells are driven by means of a pulley 15 over which passes a belt 16 driven by a motor 17 which is provided with a control system which will be hereinafter described. Since the bells may be of any preferred construction characteristic of apparatus of this type, and since the particular

construction forms no part of the present invention, they have been shown only diagrammatically. The compression bell 12 is covered by a hood 18 placed on top of the compression tank, and a similar hood 19 placed on top of the refrigerating tank covers the bell 13.

Adjacent the condenser tank and under the near the top thereof is a small feed tank 20. Liquid is supplied to this feed tank by a stand-pipe 21 connected at one end to the bottom of the feed tank and having its other end near the compression bell and in a position to collect some of the liquid carried up by the rotation of this bell. Within the feed tank is a float 23 which controls a valve 22. The valve 22 is inserted in a pipe 24 through which cooling liquid is supplied to the condenser tank. The stand pipe within the condenser tank is provided with a "bleeder" orifice 25 of relatively small aperture which is located at substantially the normal level of the cooling liquid of this tank as determined by an overflow pipe 26 as shown in Fig. 1, through which the cooling liquid is discharged from the tank.

The thermostatic control system shown in Fig. 1 comprises a thermostat 30 of any preferred construction having its heat responsive element located in the condenser tank 10 at some distance below the normal level of liquid therein. The thermal element is adapted to move a contact needle 31 between two fixed contact points 32 and 33. A similar thermostat 34 is arranged in the refrigerating tank 11 and its contact needle 35 moves between contacts 36 and 37. In each of these thermostats the needle is moved in a clockwise direction upon increase of temperature, so that in the case of thermostat 30 in the cooling tank the needle 31 will under conditions of low temperature be in engagement with contact 32, which is connected by a conductor 38 to the needle 35 of the thermostat 34. Contact 36 of thermostat 34 and contact 33 of thermostat 30 are connected by conductors 39 and 40 to one terminal of the secondary winding of a transformer 41 of the controller for motor 17. The other terminal of this coil is connected by a conductor 42 to the contact 37 of thermostat 34. The primary winding of the transformer 41 is connected by conductors 43 and 44 to the outer contacts of a main switch 45 connected to a three-phase power line. The middle contact of this switch is connected by means of a conductor 46, directly to the motor 17. The other motor conductors 47 and 48 are connected to contacts 49 and 50 of an automatic electromagnetic switch of which the actuating coil is shown at 51, but the switch arms are not shown, it being understood that they are adapted when the coil 51 is energized to connect contacts 49 and 50 with contacts 52 and 53.

53 respectively, which latter contacts are connected by conductors 54 and 55 to conductors 43 and 44 respectively, and thereby to the supply line, through switch 45.

5 For energizing the coil 51 of the automatic switch, a controlling switch of substantially similar, but smaller construction is provided. One terminal of the energizing coil 56 of this switch is connected to conductor 39 leading to the secondary of the transformer, and the other terminal is connected by a conductor 57 to the needle 31 of thermostat 30. The coil 51 of the automatic switch is connected between conductor 55 and a contact 58 of the controlling switch. The other contact 59 of this latter switch is connected to conductor 42. The corresponding upper contacts 60 and 61 of the controlling switch are connected respectively to conductors 54 and 57.

In considering the operation of the apparatus described above, it will be assumed that the refrigerating bells are at rest and that the temperature in the condenser tank 25 is sufficiently low to cause the needle 31 of thermostat 30 to engage contact 32. In order to start the motor, the main switch 45 is closed to establish a circuit through the primary winding of the transformer 41. 30 The current from the secondary winding of this transformer will then pass through the energizing coil 56 of the controlling switch, conductor 57, needle 31 of thermostat 30, contact 32, conductor 38, needle 35 of the thermostat 34, which will be in engagement 35 with contact 37 because the liquid in the refrigerating tank is assumed to be comparatively warm, thence over conductor 42 to the other terminal of the secondary coil. Energization 40 of the coil 56 of the controlling switch will establish the circuit of the coil 51 of the motor switch over conductors 43, 54, terminal 60 of the controlling switch, the switch blade thereof, terminal 58 and conductor connecting this terminal to the coil 51, conductors 55 and 44 back to the main switch 45. Energization of the coil 51 of the motor switch will cause the blades of this switch to put contacts 49 and 50 in circuit with contacts 52 and 53 respectively, so that the motor circuit is established over conductors 44, 55 and 48 leading from one blade of the main switch, and over conductors 43, 54 and 47 leading from the third 55 blade of this switch. The motor will thus be connected directly to the source of electrical supply, and will start into operation to rotate the dumb-bell.

As the dumb-bell rotates in the direction 60 indicated by the arrow in Fig. 2, the member thereof located in the condenser tank will cause a wave of liquid to follow the rotating bell, and this liquid will spill into the open end of the stand pipe 21 and flow into 65 the feeder tank 20, ultimately lifting the

float 23 to open the valve 22 controlling the supply of cooling liquid to the condenser tank. This liquid will flow into the condenser tank and will be discharged through the overflow pipe 26, keeping the rotating bell partly submerged in relatively cool liquid. The apparatus will operate in the manner characteristic of apparatus of this type, and the expansion of the refrigerating fluid in the bell or vessel 13 will begin to lower the 75 temperature of the liquid in the refrigerating tank 11.

It was assumed that at the start of the operation the temperature in refrigerating tank was high enough to cause the needle 35 of the thermostat 34 to engage contact 37, but as the temperature in this tank decreases, the needle will move away from this contact, but this will not open the motor controlling circuit because when the coil 56 85 of the controlling switch was energized, it established a holding circuit for itself from the secondary of the transformer, through coil 56, contact 61, the blade of the switch which connects this contact to contact 59 and thence over the conductor 42 back to the secondary. The controlling switch thus being held in a closed position will keep the coil 51 of the motor switch energized and the motor will continue in operation. If the 95 temperature in the refrigerating tank falls so low that the arm 35 of the thermostat 34 in this tank engages contact 36, a short circuit will be established around the coil 56 of the controlling switch. This short circuit includes conductor 39, contact 36, thermostat needle 35, conductor 38, contact 32, thermostat needle 31 and conductor 57. When coil 56 is thus short circuited, the switch associated therewith is opened to break the 105 circuit of coil 51 and thus open the motor circuit. So long as the thermostat needle 35 is in engagement with contact 36, the motor will be cut out of operation, and even if the temperature in the refrigerating tank 11 increases enough to cause the needle 35 to move away from contact 36, the motor will not be started into operation because the circuit of the coil 56 of the controlling switch cannot be established until the needle 35 of thermostat 34 engages contact 37, as has been previously explained in tracing the energizing circuit of coil 56.

If the dumb-bell is rotating and there is a sufficient flow of cooling liquid through condenser tank 10, the needle 31 of the thermostat in this tank will remain in engagement with contact 32, but if for any reason the flow of cooling liquid decreases or fails entirely the liquid in the condenser tank will 120 gradually be warmed from the effect of the bell in this tank, and finally needle 31 will move away from contact 32 and engage contact 33. In order that too long a time should not elapse between the disengagement from 125 130

4

contact 32 and engagement with contact 33, the gap between these contacts should be relatively small. When the needle 21 engages contact 33 a short circuit will be established 5 about the coil 56 of the controlling switch. This short circuit will include the conductor 57, the needle 31 of thermostat 30, the contact 33, the conductor 40 and the conductor 39 to the other side of coil 56. This short 10 circuit will be established irrespective of the condition of thermostat 34 in the refrigerating tank, and will result in the de-energization of coil 56 and the opening of the switch controlled thereby, which in turn, will open 15 the circuit of the coil 51 of the motor switch to open the circuit of the motor and prevent further rotation of the dumb-bell until the flow of cooling liquid in the condenser tank has been established and the temperature of 20 the liquid in this tank sufficiently reduced to bring the needle 31 of the thermostat into engagement with contact 32 so that the motor can again be started into operation through the controlling apparatus, by permitting the 25 coil 56 of the controlling switch to be energized.

In the arrangement described above, the thermostat in the refrigerating tank is to an extent under the control of the thermostat 30 in the condenser tank inasmuch as the former thermostat can stop or start the motor only if the latter thermostat is in the condition corresponding to a normal low temperature in the condenser tank, since a portion 35 of the circuit leading from the needle of the thermostat in the refrigerating tank includes a contact and the needle of the thermostat in the condenser tank. In Figure 3 there is shown an arrangement of thermos- 40 static control whereby either thermostat may stop the motor regardless of the position of the needle of the other thermostat, but neither thermostat can start the motor unless the needle of the other thermostat is in normal 45 circuit closing position. In the arrangement shown in this figure, the conductors 39', 42' and 57' correspond to the conductors 39, 42 and 57 of Fig. 1 and are connected to controlling apparatus as in the latter 50 figure.

The thermostat 30' in the condenser tank has two separate needles 65 and 66 insulated from each other. Needle 65 is adapted to engage a contact 67 when the normal low temperature of the liquid in the condenser tank exists, and needle 66 is adapted to engage a contact 68 upon a predetermined increase of temperature of the liquid in the condenser tank. Contact 67 is connected by 55 a conductor 69 to the conductor 42' leading to the controlling apparatus, and contact 68 is connected by a conductor 70 to the conductor 39' leading to the same apparatus. The needle 66 is connected by conductor 71 60 to the conductor 57' leading to the control- 65 ling apparatus. The thermostat 34' in the refrigerating tank is provided with a needle 72 and contacts 73 and 74. The needle 72 is connected to conductor 57' by a conductor 75. Contact 73 is connected to conductor 70 39' by a conductor 76 and contact 74 is connected to the needle 65 of thermostat 30' by a conductor 77.

With the thermostats connected as above described, the circuit for the coil 56 of the 75 controlling switch includes conductors 42' and 69, contact 67, needle 65, conductor 77, contact 74, needle 72, conductor 75 and conductor 57'. The circuit can be completed only if the needle 65 is in engagement with 80 contact 67, as it will be if a sufficiently low temperature exists in the condenser tank, and if the needle 72 is in engagement with the contact 74 as it will be under normal conditions due to a relatively high temperature 85 of the liquid in the refrigerating tank. If the temperature in the refrigerating tank falls sufficiently to cause the needle 72 to leave contact 74 and finally engage contact 73, a short circuit will be established 90 about the coil 56 of the controlling switch as follows: conductors 57' and 75, needle 72, contact 73 and conductors 76 and 39'. This short circuit will cause the deenergization 95 of coil 56, which in turn will deenergize the coil of the motor switch and stop the apparatus. If the temperature in the condenser tank rises, due to an insufficient supply of cooling liquid or any other cause, sufficiently to cause the needle 65 to disengage 100 contact 67 and the needle 66 to engage its contact 68, a short circuit will likewise be established about the coil 56 of the controlling switch as follows: conductors 57' and 71, needle 66, contacts 68 and conductors 105 70 and 39'. This will result in stopping the motor to prevent damage to the apparatus.

If the motor has been stopped, either on account of a sufficiently low temperature in the refrigerating tank, or on account of an abnormal increase of temperature in the condenser tank, the refrigerating apparatus no longer functions and the liquid in the refrigerating tank will gradually become warm, and may finally cause the needle 72 to engage contact 74, but since the circuit leading from this contact through conductor 77 includes the needle 65 of the thermostat in the condenser tank, the motor cannot be started unless needle 65 is in engagement 110 with contact 67 to complete the circuit through conductors 69 and 42' to the controlling apparatus. This arrangement insures that the thermostat in the refrigerating tank will not start the apparatus into 115 operation unless a sufficiently low temperature exists in the condenser tank to avoid any overheating of the rotary bell located therein. Viewed in another way, if the motor has been stopped by an abnormal tem- 120 125 130

perature in the condenser tank, and this temperature is lowered by adding cool liquid, or in any other way, to cause needle 65 to engage contact 67, the motor will not be started into operation until the temperature in the refrigerating tank has risen sufficiently to cause the needle 72 to engage its contact 74 to permit the energizing circuit of the coil 56 of the controlling switch 10 to be established.

It will thus be seen that both in the case of the arrangement shown in Fig. 1 and in the case of the modified arrangement shown in Fig. 3, the control is such as to take care 15 of all contingencies of operation that may occur in practice, and at the same time keep the refrigerating apparatus inactive during such times as a sufficiently low temperature exists in the refrigerating tank, thereby conserving power and preventing unnecessary wear upon the apparatus. By virtue 20 of the arrangement of the feed tank, the stand pipe and the bleeder in the stand pipe, the rotary bell located in the condenser tank is protected at all times by being sufficiently immersed in cooling liquid to impart heat to the latter to affect the thermostat therein. It will also be seen that the machine is automatically supplied with water during operation and that the cooling water supply is 25 cut off when the machine is idle.

While a three phase motor with controlling apparatus particularly adapted thereto has been shown in connection with the thermostatic control of the present invention, it will be understood that other types of motors and other kinds of motive power may be used provided that they are under the control of the thermostatic system of the present invention, and the controlling apparatus may be suitably modified to meet the demands of such other types of motors or other sources of power.

We claim:

1. In refrigerating apparatus provided with a condenser tank and a refrigerating tank and motor driven compression and expansion members mounted in the tanks, the combination of a thermostat in each tank, and means under the joint control of said thermostats for controlling the motor for driving the said members.

2. In refrigerating apparatus provided with motor driven compression and expansion members rotatably mounted in a condenser tank and a refrigerating tank respectively, the combination of a thermostat in the condenser tank and a thermostat in the refrigerating tank, and means associated with the thermostats for controlling the driving motor, said thermostats being electrically connected to each other and to the controlling means so that the thermostat in the refrigerating tank can control said means only when the thermostat in the

condenser tank is in normal circuit closing position due to a predetermined temperature of the liquid in said tank.

3. In refrigerating apparatus provided with motor driven compression and expansion members rotatably mounted in a condenser tank and a refrigerating tank respectively, the combination of a thermostat in the condenser tank and a thermostat in the refrigerating tank, and means associated with the thermostats for controlling the driving motor, said thermostats being electrically connected to each other and to the controlling means so that the thermostat in the condenser tank will act on said controlling means to stop the motor when a predetermined temperature exists in the condenser tank irrespective of the condition of the thermostat in the refrigerating tank.

4. In refrigerating apparatus provided with motor driven compression and expansion members rotatably mounted in a condenser tank and a refrigerating tank respectively, the combination of a thermostat in the condenser tank and a thermostat in the refrigerating tank, and means associated with the thermostats for controlling the driving motor, said thermostats being electrically connected to each other and to the controlling means, so that the thermostat in the refrigerating tank acts to maintain the liquid therein at constant temperature by controlling the motor through the controlling means, provided the thermostat in the condenser tank is in condition to cause the controlling device to keep the motor in operation.

5. In refrigerating apparatus provided with motor driven compression and expansion members rotatably mounted in a condenser tank and a refrigerating tank respectively, the combination of a thermostat in the condenser tank and a thermostat in the refrigerating tank, and means associated with the thermostats for controlling the driving motor, said thermostats being electrically connected to each other and to the controlling means, so that either thermostat may stop the motor regardless of the other thermostat and one of the thermostats may start the motor only if the other thermostat is in position to start the motor.

6. In refrigerating apparatus provided with motor driven compression and expansion members rotatably mounted in a condenser tank and a refrigerating tank respectively, the combination of a thermostat in the condenser tank and a thermostat in the refrigerating tank, and means associated with the thermostats for controlling the driving motor, each of said thermostats comprising a pair of contacts between which a needle is adapted to move, one of the contacts of the thermostat in the condenser tank being connected to the needle of the thermo-

stat in the refrigerating tank so that the needle of the last named thermostat exercises control over the motor controlling means only if the needle of the thermostat in the condenser tank is on the contact that is connected to the needle of the thermostat in the refrigerating tank.

7. In refrigerating apparatus provided with motor driven compression and expansion members rotatably mounted in a condenser tank and a refrigerating tank respectively, thermostats in that condenser tank and the refrigerating tank, means under the joint control of said thermostats for controlling the motor for driving the rotary members, and means controlled by the rotation of the compression member for supplying cooling liquid to the condenser tank.

8. In refrigerating apparatus, the combination of motor driven compression and expansion members rotatably mounted in a condenser tank and a refrigerating tank respectively, thermostats in the condenser tank and the refrigerating tank, means under the joint control of said thermostats for controlling the motor for driving the rotary members, said condenser tank having valve controlled feed mechanism for cooling liquid and an overflow pipe, and means controlled by the rotation of the compression member for operating the valve to admit cooling liquid to the condenser tank.

9. In refrigerating apparatus, including a condenser tank and a refrigerating tank, and motor driven compression and expansion members mounted in the respective tanks, means for controlling the flow of cooling liquid through the condenser tank whereby to regulate the temperature therein, means controlled by the rotation of the compression member for operating said means, thermostats in the condenser tank and the refrigerating tank, and means under the joint control of the thermostats for controlling the motor for driving the rotary members.

10. In refrigerating apparatus, including a condenser tank and a refrigerating tank, and motor driven compression and expansion members mounted in the respective tanks, means for controlling the flow of cooling liquid through the condenser tank whereby to regulate the temperature therein, means controlled by the rotation of the compression member for operating said means, a thermostat in the condenser tank, and means controlled by the thermostat for operating the last named means.

11. In a refrigerating apparatus, including a condenser tank and a refrigerating tank, and motor driven compression and expansion members mounted in the respective tanks, means for controlling the flow of cooling liquid through the condenser tank whereby to regulate the temperature therein,

said last named means comprising a feed tank outside of and near the top of the condenser tank, a standpipe through which the liquid is supplied to the feed tank by the rotation of the compression member, valve controlled means for supplying cooling liquid to the condenser, and a float in the feed tank for operating said valve, the standpipe having a bleed port to permit liquid supplied to the feed tank through the standpipe to flow back into the condenser tank.

12. In refrigerating apparatus including a condenser tank and an intermittently driven compression member mounted to rotate in the tank, means controlled by the temperature of the said tank for controlling the rotation of the said compression member, and means controlled by the rotation of the said member for supplying cooling liquid to the tank whereby to reduce the temperature therein.

13. In refrigerating apparatus including a condenser tank and an intermittently driven compression member mounted to rotate in the tank, means controlled by the temperature of the said tank for controlling the rotation of the said compression member, and means controlled by the rotation of the said member for supplying cooling liquid to the tank whereby to reduce the temperature therein, said means comprising a feed pipe for the liquid having a float controlled valve, a feed tank in which the float is arranged and to which liquid is delivered by the rotation of the compression member.

14. In refrigerating apparatus including a condenser tank and an intermittently driven compression member mounted to rotate in the tank, means controlled by the temperature of the said tank for controlling the rotation of the said compression member, and means controlled by the rotation of the said member for supplying cooling liquid to the tank whereby to reduce the temperature therein, said means comprising a feed pipe for the cooling liquid, a float operated valve for controlling the flow through the pipe, a feed tank in which the float is arranged, and a standpipe in the condenser tank through which liquid is supplied by the rotation of the compression member to the feed tank, said pipe having a bleed port through which the liquid supplied to the feed tank through the standpipe may flow back into the condenser tank.

15. In refrigerating apparatus, the combination with the condenser tank and the refrigerating tank, and the compression and expansion members rotating in the respective tanks, means in each tank controlled by the temperature therein, for controlling the rotation of the said members.

16. In refrigerating apparatus, the combination with the condenser tank and the refrigerating tank, and the compression and

expansion members rotating in the respective tanks, means in each tank controlled by the temperature therein, for controlling the rotation of the said members, the means in 5 the refrigerating tank being arranged to control the rotation of the said members only when the temperature in the condenser tank is below a selected point.

17. In refrigerating apparatus, the combination with the condenser tank and the refrigerating tank, and the compression and expansion members rotating in the respective tanks, means in each tank controlled by the temperature therein, for controlling the 10 rotation of the said members, and means 15

controlled by the rotation of the said members for supplying cooling liquid to the condenser tank.

18. In refrigerating apparatus provided with a condenser tank and a refrigerating tank, and a motor driven compression member mounted in the condenser tank, the combination of a thermostat in each tank, and means under the joint control of said thermostats for controlling the motor for driving said member.

In testimony whereof we affix our signatures.

ALFRED D. KARR.
KARL D. PERKINS.
